UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Original application filed February 26, 1925, Serial No. 11,697. Divided and this application filed August 25, 1925. Serial No. 52,319.

This invention aims to provide an improved fastener stud unit.

The application is a division of my prior application, Serial No. 11,697, filed February 26, 1925.

In the drawings, which illustrate a preferred embodiment of my invention:—

Figure 1 is an elevation view of a window and window frame of a vehicle body, showing one use of my invention;

Fig. 2 is a section on the line 2—2 of Fig. 1, showing the trim strip secured to the window frame by stud and socket fastening means;

Fig. 3 is a plan view of a portion of a trim strip showing a stud element unit secured thereto;

Fig. 4 is a side elevation of the stud unit;

Fig. 5 is an underside view of the stud unit;

Figs. 6 and 7 illustrate the steps in the forming of the casing part of the stud unit; and

Fig. 8 is a section through the trim strip showing a stud unit being secured thereto by the use of a suitable tool.

Referring to the drawings, I have shown a trimming installation particularly, though not exclusively, useful on automobile bodies.

The installation, as illustrated in Figs. 1 and 2, includes the window and window frame part 1 of the body (shown for illustration only), an upholstery fabric 2 covering portions of the inside of the body and overlying the edges of the window frame part 1 and a plurality of wooden trimming strips 3 secured to the frame part 1 by stud and socket fastener elements.

The frame part 1 is herein shown as pressed metal and presents a plurality of stud-receiving apertures 1^a for receiving the heads of the studs presented by the trim strips.

The trim strip is relatively long and thin and, because of its thinness, the fastening elements are constructed with a view to being secured to the wood without splitting or passing through it.

Each stud unit includes a casing part 4 and a socket-engaging part 5 and is secured to the trim strip 3 as hereinafter more fully described.

The socket-engaging part is pressed from a single piece of metal and presents a con-

tractible and expandible head 6, a neck 7 and a relatively thin flat base portion 7^a. The casing part is also pressed from a single piece of metal (Figs. 6 and 7) and has an upstanding peripheral wall 8, an inner base or back flange portion 9, a prong-presenting portion 10 depending from the inner free edge of the base flange 9 and a plurality of attaching prongs 11 initially bent outwardly from the prong-presenting portion 10, as best illustrated in Figs. 4, 5 and 8. The attaching prongs 11 are first formed as a dome (Fig. 6), which is slotted to provide the several prongs which are thereafter bent outwardly from the dome, as shown in Fig. 6, to the initially bent position, as shown in Fig. 7.

Assembly of the stud unit parts is effected by placing the socket-engaging part, base portion 7^a first into the casing and then bending a portion of the upstanding wall 8 over the base and forming the outer or front flange 12, as best illustrated in Fig. 2.

The base 7^a of the socket-engaging or stud part is smaller in diameter than the diameter of the casing. The aperture 13, in the front flange 12, is larger in diameter than the head 6 and neck 7 of the stud. These clearances between the parts, as stated, permit lateral shifting of the stud part relative to the casing for alignment with its cooperating stud-receiving aperture 1^a, presented by the body part 1.

Assembly of the stud units with a trim strip 3 is effected by first forming two concentric recesses 14 and 15 at the inner face of the strip and securing the casing part 4 of the stud unit in the recesses. The attaching prongs 11 enter the smaller recess 15 (Fig. 8) and are forced outwardly into the wall of the recess beneath the annular seat 16 by a suitable tool 17, which seats against the front face of the casing, forces the casing into the recess 14 against its seat 16, as best illustrated in Fig. 2. The seat 16 limits the movement of the casing 4 of the stud unit so that when the prongs 11 are embedded in the strip 3, the front flange 12 of the casing 4 lies flush with the inner face of the trim strip 3. Only the head and neck of the socket-engaging part 5 extend beyond the inner face of the strip 3.

The prongs 11 are thus engaged with the trim strip at a sufficient depth below the

inner face of the strip so that they will be less likely to splint out of the wood than if it were attached nearer the inner base of the strip.

5 During engagement of the studs with the stud-receiving apertures 1*, the socket-engaging parts 5 shift relative to the casing part 4 to align with the apertures. They are then pressed into the apertures 1*, as shown 10 in Fig. 2, so that the trim strip squeezes the upholstery fabric 2 against the body part 1 to hold it in place. Holes 18 are provided in the fabric 2 adjacent the apertures 1* in the body part to permit the heads of the 15 studs to pass therethrough.

Removal of the trim strip may be easily and quickly effected by inserting a suitable tool between the fabric 2 and the strip and prying upwardly to pull the stud heads free 20 from the body 1 of the vehicle or other like support to which the strips are attached.

While I have shown and described a preferred embodiment of my invention, it will be understood that I have done so for purposes of clarification rather than limitation, my invention being best defined in the following claims.

Claims—

1. A fastener comprising, in combination, 30 a stud having a head and a base, a stud-securing part presenting a face underlying said base, a rim surrounding said base while providing clearance permitting lateral shifting of said stud relative to said securing 35 part and a flanged-in rim on said securing part overlying said base at the side thereof

opposite said face, and attaching prongs integral with said securing part and projecting from said face in a direction opposite to that in which said head extends. 40

2. A fastener stud unit comprising, in combination, a casing part presenting an annular wall, a front flange, a back flange and a depending prong-presenting portion at the free edge of said back flange, a resilient 45 socket-engaging part having a relatively thin base portion located in said casing between said flanges and presenting a contractible and expansible socket-engaging head and neck passing through an aperture in said front flange for engagement in a stud-receiving aperture, said socket-engaging part laterally shiftable relative to said casing for alignment with the stud-receiving aperture. 50

3. A fastener stud for trimming installations comprising, in combination, a socket-engaging part and a casing part, said socket-engaging part presenting a flat base, head and a neck, two annular flange portions presented by said casing part and between 60 which the said base is located while the head and neck of the stud extend therefrom at one side of said casing, said casing presenting at the opposite side from said head and neck, at the inner edge of one of said flange 65 portions, a plurality of initially bent attaching prongs for securing said casing to a support.

In testimony whereof, I have signed my name to this specification.

FRED S. CARR.
